UNITED STATES PATENT OFFICE.

OLE O. STORLE, OF TACOMA, WASHINGTON.

INTERNAL-COMBUSTION ENGINE.

1,068,710.

Specification of Letters Patent.

Patented July 29, 1913.

Application filed September 15, 1911. Serial No. 649,416.

To all whom it may concern:

Be it known that I, OLE O. STORLE, a citizen of the United States, residing at Tacoma, in the county of Pierce and State of Washington, have invented certain new and useful Improvements in Internal-Combustion Engines, of which the following is a specification, reference being had to the accompanying drawing, forming a part 10 thereof.

The main objects of this invention are to utilize to the fullest extent the expansive force of the exploded charges and thereby economize power and prevent or reduce the 15 noise of the exhaust without a muffler; to avoid dead centers, and generally to improve the construction and operation of engines of this class.

It consists in the construction, arrangement and combination of parts as herein-after particularly described and pointed out in the claims.

In the accompanying drawing like characters designate the same parts in the several figures.

Figure 1 is a vertical longitudinal section of an engine embodying the invention, the pistons being shown in the positions they occupy at the end of the suction stroke; Fig. 2 30 is a similar section showing the pistons in the positions they occupy at the end of the compression and at the end of the exhaust stroke; Fig. 3 is a similar section showing the pistons in the positions they occupy at 35 the end of the explosion or working stroke; and Fig. 4 is a plan view of the engine.

The cylinder *a*, which is comparatively long and open at the ends, is provided in the usual manner with a water or cooling jacket 40 *b*, and with an inwardly projecting shoulder *c* forming a stop for one of the pistons, as hereinafter explained.

d and *e* are oppositely working trunk pistons fitted in the cylinder on opposite sides 45 of the shoulder or stop *c* with their closed ends toward the middle of the cylinder, which is provided with inlet and exhaust ports opening into the space which forms the explosion or combustion chamber be- 50 tween the two pistons when they are at the inner limits of their movement, only the exhaust port *f* being shown. The engine is also provided with inlet and exhaust valves, valve operating mechanism and igniting devices, which may be of the usual or any suitable construction, and are not shown.

Adjacent to one end of the cylinder the engine is provided with a crank *g* which has a longitudinally shifting connection with the piston *e*, whereby said piston is permitted to dwell at the inner limit of its travel during the suction stroke of the other piston *d*, thereby reducing the space for the admission of the explosive charge on the suction stroke of the piston *d* and permitting it to expand when exploded during the simultaneous outward movement of both pistons into a much larger space, so as to utilize to the fullest extent the explosive force of the charge, and without the intervention of a muffler, to avoid or materially reduce the noise produced by the exhaust. This shifting connection between the crank *g* and piston *e* may be made as shown, by means of a head or plunger *h* fitted and movable lengthwise in the piston *e* and directly connected by a rod or pitman *i* with the crank *g*. 60 65 70 75

To insure the dwelling of the piston *e* at the inner limit of its travel during the suction stroke of the piston *d*, the plunger *h* 80 is formed through its inner end, which is otherwise closed, with one or more ports or passages *j*, and is provided with an inwardly opening valve *k* which closes said ports or passages when the plunger moves 85 inward. To permit of the free inward movement of the plunger *j* in the piston *e* and at the same time prevent it from coming into violent contact therewith at the inner limit of its stroke, the piston *e* is formed 90 with one or more longitudinal air passages *l* leading from the interior thereof at an intermediate point in the stroke of the plunger *h* through the outer end of the piston to the atmosphere. 95

*The piston *d* is connected by a rod or pitman *m* with one arm of a lever *n* which is fulcrumed in the frame or bed of the engine at the opposite end from the crank *g*. The other arm of this lever is connected by a rod *o* with a crank pin *p* on the flywheel *q* of the engine, or on the crank shaft in line with the crank *g* with which the piston *e* is connected through the plunger *h* and rod *i*. 100

In the operation of the engine, which is 105 of the four-cycle type, during the suction stroke of the piston *d*, which draws an explosive charge into the cylinder, the piston *e* is held as shown in Fig. 1, at the inner limit of its movement by the vacuum or partial 110 vacuum thus produced in the cylinder by the piston *d*; against the shoulder *c*, while

the head or plunger *h* is drawn outward. During the return stroke of the piston *d* and plunger *h* the charge is compressed between the pistons *d* and *e*, the outward movement 5 of the piston *e* by the compression of the charge being resisted by the inward movement of the plunger *h* and the compression of the air therein by said plunger. The charge being ignited and exploded when the 10 pistons and plunger are at or near the inner limits of their travel, forces both pistons *d* and *e* simultaneously outward as shown in Fig. 3, and acts through their connections hereinbefore described, to turn the crank 15 shaft, the piston *e* and plunger *h*, operating together as one, through the connecting rod *i* on the crank *g* on the explosion or working stroke. The space between the pistons *d* and *e* into which the charge expands after its 20 explosion, as shown in Fig. 3 being much greater than the space into which it is admitted on the suction stroke of the piston *d*, as shown in Fig. 1, the expansive force of the charge is utilized to the fullest extent 25 and its pressure being thus reduced, it escapes from the exhaust port with little or no noise.

The pistons *d* and *e* and the parts of the cylinder *a* in which they work, may be made 30 of different diameters instead of the same diameter as shown, the engine may be provided for use in automobiles or other purposes with a number of cylinders, and various other changes in the details of construction 35 and arrangement of parts may be made within the scope of the invention as defined in the following claims.

I claim:

1. In an internal combustion engine the 40 combination of a cylinder, two oppositely working pistons fitted therein, and a crank connected with said pistons, one of the pistons having a longitudinally shifting connection with the crank and being adapted to 45 dwell at the inner limit of its travel during the suction stroke of the other piston.
2. In an internal combustion engine the 50 combination of a cylinder, two oppositely working pistons fitted therein, a plunger fitted and movable lengthwise within one of said pistons and provided with a port and

with an inwardly opening valve controlling said port, and a crank connected with said plunger and with the other piston.

3. In an internal combustion engine the 55 combination of a cylinder, oppositely working pistons fitted therein, a plunger fitted and movable lengthwise in one piston which piston has an air passage leading from an intermediate point in the interior thereof to 60 the atmosphere, and a crank connected with said plunger and with the other piston.

4. In an internal combustion engine the 65 combination of a cylinder, oppositely working pistons fitted therein, a plunger fitted and movable lengthwise in one piston which piston has an air passage leading from the interior thereof at an intermediate point in the stroke of the plunger to the atmosphere, said plunger having a port opening to the 70 atmosphere from the interior of said piston, an inwardly opening valve controlling said port, and a crank connected with said plunger and with the other piston.

5. In an internal combustion engine the 75 combination of a cylinder, oppositely working pistons fitted therein, a crank at one end of the engine connected by a rod with one piston, a lever at the other end of the engine having an arm connected by a rod 80 with the other piston and a rod connecting the crank with the other arm of said lever both pistons working when forced apart to turn the crank.

6. In an internal combustion engine the 85 combination of a cylinder comprising two parts each communicating with the other at one end, reciprocating pistons fitted therein, and a crank shaft connected with and adapted to be turned by the joint action of 90 said pistons, one of said pistons having a longitudinally shifting connection with the crank and being adapted to dwell at the limit of its travel toward the intercommunicating ends of the cylinder parts while the 95 other piston makes its suction stroke.

In witness whereof I hereto affix my signature in presence of two witnesses.

OLE O. STORLE.
